UNITED STATES PATENT OFFICE.

DANIEL M. SOMERS, OF BROOKLYN, NEW YORK.

DESIGN FOR BOXES.

Specification forming part of Design No. **11,548**, dated December 23, 1879; application filed November 14, 1879.
[Term of patent 7 years.]

To all whom it may concern:

Be it known that I, DANIEL M. SOMERS, of the city of Brooklyn, in the county of Kings and State of New York, have invented a new and Improved Design for Boxes, of which the following is a specification.

My invention relates to boxes for holding cakes of soap, matches, or other articles; and it consists, essentially, in a box and cover therefor made in the form of a parallelogram with rounded corners, the cover, and preferably also the bottom of the box, having a molding extending around their edges, and the said box being also provided with rounded protuberances or feet, which are arranged near the edge, so as to form a continuation of the bottom molding.

It also consists in a novel design for the ornamentation of the top of the cover of the box.

In the accompanying drawings, Figure 1 represents a perspective view of a box embodying my design, and Fig. 2 represents a section thereof.

Similar letters of reference designate corresponding parts in both figures.

A designates the box proper, and B the lid or cover therefor. They are both made in the form of a parallelogrammic figure having rounded corners.

The cover B is provided around its upper edge with a molding, a, (represented here as consisting of an ovolo,) and the box proper is also provided around its lower edge or angle with a molding, b, of similar form to the molding a.

The bottom of the box is also provided at its corners with rounded protuberances or feet c, which are arranged near the edge of the molding b, and the vertical profile of each of

which forms a continuation of the vertical profile of such molding.

Upon the top of the cover B is delineated an ornamental design, consisting of a centrally-arranged scroll, d, and roses e, and lilies-of-the-valley f, arranged above and below said scroll, and mingled with grasses.

What I claim as my invention, and desire to secure by Letters Patent, is—

1. The design for a box-cover, consisting of the parallelogrammic figure having rounded corners, and the molding a, extending around the top of the same, substantially as specified.

2. The ornamental design for the top of a box-cover, consisting, essentially, of the scroll d, having the flowers and grasses arranged above and below it, substantially as specified.

3. The design for a box, consisting, essentially, of the parallelogrammic figure having rounded corners, and the molding b, extending around the bottom thereof, substantially as specified.

4. The design for a box, consisting, essentially, of the parallelogrammic figure having rounded corners, the molding b, extending around the bottom thereof, and the rounded feet c, arranged so that their several vertical profiles form continuations of the vertical profile of the said molding b, substantially as specified.

5. The design for a box and cover, consisting, essentially, of a parallelogrammic figure having rounded corners, having the molding a around the top of the cover and the molding b around the bottom of the box, substantially as specified.

D. M. SOMERS.
